UNITED STATES PATENT OFFICE.

HENRY DE SMITH, OF ROCHESTER, NEW YORK, ASSIGNOR TO M. D. KNOWLTON COMPANY, OF ROCHESTER, NEW YORK, A CORPORATION OF NEW YORK.

SAFETY OPERATING MECHANISM.

1,280,970.

Specification of Letters Patent.

Patented Oct. 8, 1918.

Application filed September 22, 1914, Serial No. 862,893. Renewed March 5, 1918. Serial No. 220,618.

To all whom it may concern:

Be it known that I, HENRY DE SMITH, a citizen of the United States, and resident of Rochester, in the county of Monroe and State of New York, have invented certain new and useful Improvements in Safety Operating Mechanism, of which the following is a specification.

This invention relates to safety devices intended to prevent the operator of a press, punching machine, box staying machine or the like, from becoming injured, if his hand happens to be under the work-performing element of the machine. The invention relates more particularly to that type of safety device in which power is transmitted to the work-performing element only when the same is in close proximity to the work. At all other times, no pressure is applied to the work-performing element, and, therefore, if the operator's hand, or any other obstruction, is encountered, no harm will be done.

The object of the present invention is to provide an improved device of this character which is simpler in its construction than previous devices and more efficient in its operation.

The improved safety device or safety operating mechanism may be applied to numerous different machines, but it has been illustrated in the accompanying drawings as applied to a box staying machine.

Referring to the drawings:

Figure 1 is a front elevation of a portion of a box staying machine showing the safety operating mechanism applied thereto;

Fig. 2 is a side elevation of the construction shown in Fig. 1;

Fig. 3 is an enlarged detail view of the safety operating mechanism or safety link; and

Fig. 4 is a side elevation, partly in section, of the construction shown in Fig. 3.

The box staying machine illustrated is of the usual construction, and comprises a movable die A carried by the slide B and a stationary die or anvil C. The slide B is provided with a pin D, which is connected, by

means of a pitman or link, to the usual eccentrically mounted crank pin E, provided on the actuating shaft F.

The link above referred to between the crank pin E and the pin D is so constructed as to constitute the safety device hereinbefore mentioned. In the present instance, the safety device or safety link comprises the link proper 1, which is mounted at its upper end on the crank pin E, a bushing 2 preferably being interposed between the journal of the crank pin and the bearing of the link. The lower end of the link 1 is provided with an elongated opening 3, in which the pin D is adapted to engage, and in which it is freely slidable.

The link 1 is provided, at its upper end, with a rearwardly directed hub portion encircling the crank pin E, and serving as a journal for a depending gag 5. A spring 6, positioned in a recess 7, common to both the link 1 and gag 5, acts against a plug 8 screwed into the gag 5, and tends to hold said gag in the substantially vertical position shown in Fig. 3. When in such position, power will be transmitted from the crank pin E, through the intermediary of the gag 5, to the pin D.

The gag is normally held in the position represented by dot and dash lines in Fig. 3, by means of a cam 9, preferably formed as an integral part of the crank pin E. This cam acts upon a cam lever 10, which is riveted to a depending finger 11, journaled in the link 1, as shown at 12. The depending finger 11 is positioned at the inner side of the link 1, and engages in an appropriately formed depression or recessed portion 13 in the gag 5, as best shown in Fig. 4. From this construction, it is obvious that pivotal movements of lever 10 around 12 as a center will swing the finger 11, and thereby move the gag 5 around the crank pin E as an axis.

The cam 9 is so formed that just after the work-performing element, that is the movable die A, leaves the work, and the link 1 starts its up stroke, the cam lever 10 will be shifted by the cam to the dotted line position shown in Fig. 3. This movement of

the cam lever 10 will be transmitted to the gag 5 by means of the finger 11 and cause the gag to assume the position shown by the dot and dash lines in Fig. 3. The cam 9 will 5 hold the gag in this position until the die A comes within approximately $\frac{1}{8}$ of an inch of the work to be operated upon on the down stroke of the link, at which time, the cam 9 will assume the position shown in Fig. 3, and 10 permit the lever 10 to swing the gag 5 to its substantially vertical position. The actuating means, or the crank pin E, is then positively connected with the pin D, and the gag serves as rigid means for transmitting 15 pressure from the actuating means to the movable die A. If, however, the movable die A meets with an obstruction, such as the operator's hand, during the down stroke of the link, the movable die A and pin D will 20 be held stationary by the obstruction, and as the gag is in its inoperative position, the link 1 will move downwardly relative to the pin D, due to the provision of the elongated opening 3. As no pressure is at that time 25 being applied to the pin D, it is obvious that the operator's hand, or other obstruction, will be uninjured. The movable die A must be approximately $\frac{1}{8}$ of an inch from the work 30 before pressure can be applied to the die by the gag, and, therefore, any obstacle greater in thickness than $\frac{1}{8}$ of an inch, will cause no harm, as the link and gag will merely descend under such circumstances without transmitting pressure to the die. On the up 35 stroke of the link, the movable die A, slide B, and pin D are lifted by the link, and on the down stroke of the link, the pin D still remains in the lower part of the opening 3, due to the weight of the slide. The pin D, 40 therefore, always occupies the position shown in Fig. 3, to wit, in the lower part of the opening 3, except when the die meets with an obstruction, at which time, the link will move downwardly relative to the pin 45 D and cause said pin to occupy the upper part of the opening 3.

From the foregoing construction, it will be noted that practically no resistance is offered to the yielding or relative movement 50 of the parts when an obstruction is encountered, as no parts have to slide upon each other, or telescope, as has been the case in previous devices of the same general character.

55 What I claim is:—

1. In a machine of the kind described, the combination with the work-performing element and its actuating means, of a link 60 yieldingly connected with the work-performing element to cause the latter to operate when the actuating means is in operation but designed to permit the work-performing element to yield with respect to the link if an obstruction is encoun-

tered during the working stroke of the work-performing element, a normally inoperative gag pivotally associated with the actuating means and adapted to be shifted to an operative position between the actuating means and the work-performing element in 70 which it acts as a rigid power-transmitting means, and means including a cam associated with the actuating means for automatically effecting shifting of the gag to its operative position on each working stroke of the work-performing element just prior to the engagement of the work by the work-performing element. 75

2. In a box staying machine and the like, having a work-performing element and a crank pin from which said element is actuated, a safety link mounted on said crank pin and having a loose connection with the work-performing element, a normally inoperative gag mounted to swing about said crank pin as an axis and adapted to occupy a position between the crank pin and the work-performing element in which it acts as a rigid power-transmitting means, a cam associated with the actuating means, and means whereby said cam controls the movement of said gag. 85

3. In a machine of the kind described, the combination with the work-performing element and its actuating means, of a link 90 yieldingly connected with the work-performing element to cause the latter to operate when the actuating means is in operation but designed to permit the work-performing element to yield with respect to the link if an obstruction is encountered during the working stroke of the work-performing element, a normally inoperative gag pivotally associated with the actuating means and adapted to be shifted to an operative position between the actuating means and the work-performing element in 100 which it acts as a rigid power-transmitting means, means tending to shift the gag to its operative position, and means associated 105 with the actuating means for controlling the movement of the gag so that it will be automatically shifted to its operative position on each working stroke of the work-performing element just prior to the engagement of the work by the work-performing element. 110

4. In a machine of the kind described having an actuating crank pin and a pin associated with the work-performing element, 120 of a link connecting the two and loosely connected with the pin of the work-performing element, a normally inoperative gag pivotally associated with the crank pin and adapted to be shifted to an operative 125 position in which it serves as a rigid power-transmitting member between the crank pin and the pin of the work-performing ele-

ment, and means including a cam associated with the crank pin for automatically effecting shifting of the gag to its operative position on each working stroke of the work-
5 performing element just prior to the engagement of the work by the work-performing element.

Signed at Rochester, in the county of Monroe and State of New York, this 12th day of September, A. D. 1914.

HENRY DE SMITH.
